(57) CLAIM

The ornamental design for a protective medical device accessory, as shown and described.

DESCRIPTION

FIG. 1 is a front perspective view of a protective medical device accessory of the invention;

FIG. 2 is a right side view thereof;

FIG. 3 is a front view thereof;

FIG. 4 is a rear view thereof;

FIG. 5 is a bottom view thereof; and,

FIG. 6 is a top view thereof.

The broken lines illustrate portions of the protective medical device accessory that form no part of the claimed design.
